CLAIM

I claim the ornamental design for a bottle, as shown and described.

DESCRIPTION

FIG. 1 is a front perspective view of the bottle showing my design.

FIG. 2 is a front elevation view thereof;

FIG. 3 is a back view thereof;

FIG. 4 is a side view;

FIG. 5 is an opposite side view thereof;

FIG. 6 is a top plan view thereof; and,

FIG. 7 is a bottom view thereof.

The broken line text is presented for illustrative purposes only and forms no part of the claimed design.
